CLAIM

The ornamental design for a handyman tray, substantially as shown and described.

DESCRIPTION

FIG. 1 is a top perspective view of a handyman tray showing my new design;

FIG. 2 is a top plan view thereof. The bottom plan view is essentially identical in outline configuration except for the absence of the upstanding peripheral wall;

FIG. 3 is a left side elevational view of FIG. 1;

FIG. 4 is a front elevational view of FIG. 1;

FIG. 5 is a rear elevational view of FIG. 1; and

FIG. 6 is a right side elevational view of FIG. 1.

FIG. 1

FIG. 2

FIG. 3

FIG. 4

FIG. 5

FIG. 6
